UNITED STATES PATENT OFFICE.

LOUIS H. MORIN, OF NEW YORK, N. Y., ASSIGNOR TO A. S. PHILLIPS, OF NEW YORK, N. Y.

MACHINE FOR MAKING PYJAMA FROGS.

Application filed August 13, 1926. Serial No. 129,075.

This invention relates to a machine for making frogs or button hole loops commonly used on pyjamas, dressing gowns and similar garments. These frogs are made from a specially woven tape or braid provided along its edges with cords slideable within the woven fabric of the tape. The tape is curved flatwise to form the characteristic loops by pulling one of these cords while holding the other fixed relative to the tape, the contour and position of each loop being determined by the length of cord pulled and the place at which the fixed cord is held. So far as I am aware all pyjama frogs today are made by hand and although the operators acquire a high degree of skill it is difficult to reproduce hundreds of these frogs of exactly the same pattern, and besides, as is usually the case with hand labor, the output is relatively small. It is the object of the present invention to provide a machine for making these frogs.

In the machine which I have designed a unit length of tape is held in position by a movable gripper which bears against one of the cords only, and a movable pulling member which pulls the other cord. As the movement of the pulling member curves the tape the gripper is moved forward step by step by means synchronized with the pulling member, thus changing the effective point at which the fixed cord is held, and hence determining the curvature and position of the loops. As the movements of the gripping and pulling members are synchronized in accordance with a definite predetermined plan, it is possible to produce frogs of any desired pattern, all exactly alike. In order to make the machine automatic and continuous in its operation I utilize the moving member which pulls the cord during the looping operation, to unwind a unit length of tape from a supply spool and draw it under the gripper, and, in view of the fact that during the looping operation the pulling member must pull on one of the cords only, I cause it to draw the tape into position under the gripper through a pull exerted on this same cord. The machine is thus all set for the looping operation as soon as the gripper engages the tape which it does at the proper time. I also employ means for automatically cutting off each unit length of tape just before the looping operation, and means for severing the extending cord from the com-

pleted frog. And in order to insure that the pulling member seize its proper cord only and not the fabric of the tape, I have provided a finger which strips the fabric from the forward end of the remaining tape after each cutting thus leaving the cord exposed and in readiness to be seized.

In my co-pending application Serial No. 129,076 filed concurrently herewith I have illustrated and described a machine in which a plurality of separate grippers are employed and released in timed sequence as the other cord is pulled. Except for this and the difference in the mechanisms for operating these two types of grippers, the two machines are identical.

In the accompanying drawings I have illustrated a machine embodying the principles of my invention. It is to be understood, of course, that this machine might be modified in many respects and still embody the invention, this being particularly true of the operating mechanism illustrated. In these drawings, Figure 1 is a plan view of the machine; Figure 2 is a transverse vertical section on an enlarged scale taken along line 2-2 of Figure 1; Figure 3 is a front elevation of the machine; Figure 4 is a section taken along line 4-4 of Figure 3; Figure 5 is an enlarged detailed section taken along line 5-5 of Figure 1; Figure 6 is a detailed section taken along line 6-6 of Figure 5; Figure 7 is a horizontal section taken along line 7-7 of Figure 2 and Figures 8, 9, 10, 11, 12, 13 and 14 are views of the frog in various stages of manufacture, Figure 14 being a view of the completed frog.

The machine illustrated in these drawings comprises a base 1 on which are mounted a plurality of standards 2 which support the various operating elements of the machine. A bracket 3 is secured to the left-hand standard and carries a spool 4 which supplies the tape 5 from which the frogs are made. The tape from this spool is unwound, cut off in unit lengths, and formed into loops of the desired curvature and position to form the completed frog. Power is supplied to the machine through a pulley 6 to which the main shaft 7 of the machine is connected and disconnected by means of a clutch 8 controlled by a clutch arm 9. I shall first describe the mechanism for drawing the unit length of tape from the spool,

Extending across the front of the machine is a horizontal track or guide-way 10, T-shaped in cross section, upon which is mounted a carriage 11 which is moved back and forth along this guide-way by means of a link-work consisting of five interconnected links 12, 13, 14, 15 and 16, the links 14 and 16 being pivotally mounted upon the fixed bosses 17 and 18. Fixed upon the 10 shaft 7 is a cylindrical cam drum 20 provided with a peripheral cam groove 21. The link 16 is provided with a cam follower 22 extending within the cam groove 21, and the reciprocation of the carriage 11 is thus 15 controlled by the cam drum 20. The link 12 which is pivotally connected with the carriage 11 terminates in a dog 24 fixed relative to the link 12 so that when the carriage is moving toward the right, Figure 20 1, the dog 24 is swung clockwise and into contact with a plate 25 forming a part of the carriage. When the carriage 11 is moved toward the left, the dog 24 is swung counter-clockwise out of contact with the 25 plate 25, but limited in its counter-clockwise swinging by means of a suitable stop 26 on the carriage which engages the link 12.

The tape 5 as it leaves the spool extends 30 through a guide-slot 27 in the bracket 3 and into the space between the dog 24 and the plate 25 when the carriage is in its extreme left-hand position, as shown in Figure 1. The cam drum 20 then moves the carriage to the right, acting through the 35 various connecting links described above, and swings the dog 24 inward to seize the lower of the two edge cords of the projecting tape, as shown most clearly in Figure 2. Continued movement of the carriage toward the right draws a unit length of tape 40 across the machine and after this unit length has been severed from the tape on the spool, the machine is in readiness for the looping operation. I shall now describe 45 the means for cutting off this unit length of tape which has been drawn into looping position.

Pivoted mounted at 28 upon the left-hand standard 2 of the machine is a pair of shears 29, the cutting plane of which is just 50 within the extreme left-hand position of the dog 24. These shears are operated by means of a cam disk 30 fixed upon the shaft 7 and provided with a facial cam groove 31 55 in which is positioned a cam follower 32 mounted upon the ends of a bell-crank lever 33 pivotally mounted upon the standard 2 at 34, the other arm of which is connected to the shears through links 36. Cam 30 is so 60 designed that when the carriage has unwound a predetermined unit length of tape, the shears 29 operate to sever this unit length from the tape on the spool but leave the forward end of the new tape in position to be 65 gripped by the carriage on its return move-

ment. The shearing action just described does not take place, however, until the unit length of tape has been securely gripped in position for looping, and I shall now describe this gripping means. 70

Extending across the front of the machine, just above the guide-way 10 is a plate 38 pivoted along its upper edge at 39. This plate is swung about the axis 39 through a small arc, and for a purpose to be described 75 later, by means of an arm 40 carrying at its inner end a cam follower 41 controlled by the peripheral cam face of the cam 30. Also extending across the front of the machine beyond the plate 38 and above and beyond the guide-way 10 is a second track or guide-way 42 upon which a carriage 43 is mounted for reciprocation. This carriage 43 carries a horizontally disposed roller 44, positioned just opposite the lower inner face 80 of the plate 38, and mounted upon a shaft 45 journaled within the carriage 43 the shaft 45 carrying at its upper end a pinion 46 which meshes with a fixed rack 47 extending along the front of the machine. 85

When the carriage 11 is drawing the unit length of tape across the machine, the pull, as explained above, is exerted through the lower edge cord. During this movement the plate 38 is swung into its outer position, as 90 illustrated in Figure 4, and the upper edge cord is passed between the roller 44 and the plate 38, the carriage 43 at this time being situated near the left-hand side of the machine. As soon as the desired length of tape has been unwound, the cam 30, acting 95 through the arm 40, swings the plate 38 downward, securely gripping the upper edge cord of the tape between the lower inner face of the plate and the roller 44. This much having been accomplished, the tape is securely held and the shearing action immediately follows. The tape is then in position for the looping operation which I 100 shall now describe. 105

The roller 44 and the plate 38 having gripped the upper edge cord of the tape, somewhere intermediate its ends, but close to the left-hand end, further movement of the carriage 11 to the right pulls the lower edge cord and curves the left-hand end of the tape as illustrated in Figure 8. To form a single loop of the desired curvature and to form a plurality of such loops in proper spaced relation, it is necessary to move forward the effective point at which the tape is gripped. I do this by moving the roller 44 forward along the plate 38. This movement is effected by link-work similar to that which controls the movement of the carriage 11, and consisting of links 48, 49, 50, 51 and 52. Link 52 is pivoted upon lug 53 extending rearwardly from the guide-way 10, and the links 49 and 50 are pivoted upon the fixed upright 54, these latter two links 115 120 125 130

being each fixed to a pivot pin 55 and moving in unison. The link 52 is provided with a cam follower 57 which extends upward within the peripheral cam groove 58 of a cam drum 59 fixed upon the shaft 7 and designed to effect reciprocation of the carriage 43.

The operation of the machine during the looping operation is as follows: The carriage 11 moves to the right, while the carriage 43 follows step by step. The first curve, as illustrated in Figure 8, is made before the carriage 43 and gripping roller 44 have moved. Thereupon the cam drum 59 moves the roller 44 forward a step and holds it stationary until the semi-circular curve of Figure 9 is made. The roller then moves forward another step and the complete loop of Figure 10 results. The next step is somewhat longer to allow for the straight length of tape between the first loop and the next one to be formed as illustrated in Figure 11. And so on until the completed frog is made. In order to insure rotation of the roller 44 and to guard against a sliding movement which would tend to move the tape forward bodily and interfere with the proper spacing of the loops, the rack and pinion 46 and 47 have been provided.

At the conclusion of the looping operation the lower edge cord extends beyond the end of the tape and should be cut off. This is accomplished by means of a knife 60 pivoted at 61 on the right-hand standard 2 operating with a shear blade 62, and operated by means of an arm 63 carrying a cam roller 64 which is controlled by a cam 65 on the peripheral face of the cam drum 20. This cam is so timed that when the frog has been completed, the extending cord is severed and the completed frog deposited upon an off-bearing belt 66, operated by means of a chain and sprocket connection 67 from the shaft 7. The frogs thus looped are complete except for a light stitching designed to keep them in proper shape during packing and shipping.

The cycle just described is now repeated, the carriages 11 and 43 being moved to the left, the carriage 11 in position to seize and unwind a new unit length of tape, and the carriage 43 in readiness to grip the new unit length at the beginning of the looping operation. It is necessary, however, that the dog 24 should seize only the lower edge cord of the new tape, as otherwise when the looping operation begins and the tape itself is held stationary, the fabric would be torn. I shall now describe the mechanism for preparing the forward end of the new tape for seizure by the dog 24.

Pivoted on the bracket 3 and beyond the shears 29 is an arm 68 provided at its inner end with a finger 69 designed to be swung against the fabric of the forward end of the

tape between the two edge cords, but normally held out of contact with the tape by means of a spring 70 connecting the outer end of the arm 68 with an extension on the bracket 3. The inward swinging movement of the finger 69 is effected as follows: The arm 68 is provided intermediate its ends with an extension 71 which is engaged by a set-screw 72 mounted upon the outer blade of the shears 29 when the shears are swung into wide open position to swing the finger 69 inward against the forward end of the tape, this movement stripping the edge cords and leaving them bare for a sufficient distance to permit the dog 24 to get a clean grip upon the lower cord. When the shears 29 are operated to cut the tape the spring 70 swings the finger 69 out of the way. The cam groove 31 is so designed that after the cutting operation the shears are opened only enough to free them from the tape and swing them out of the path of the dog 24, but not enough to cause contact between set screw 72 and extension 71. Thus the spring 70 holds the finger 69 out of contact with the tape and permits the dog 24 freely to grip and draw the tape.

The relative movement of the two carriages 11 and 43 determines the pattern to which frogs are made, and this pattern can be varied by varying this relative movement. This can be done through changes in the cam drums 20 and 59.

The machine of my invention is capable of producing frogs rapidly, continuously and automatically as long as any tape remains on the spool. Not only can a single operator with one of these machines greatly exceed the output per hour of many hand workers, but the machine-looped frogs are more perfectly made and can be reproduced exactly to any desired pattern.

I claim:

1. A machine for making pyjama frogs from tape having slideable edge cords comprising the combination of means for gripping the tape at one edge, means for pulling the cord in the other edge to form a curve in the tape, and means synchronized with the pulling means for releasing the tape from the gripping means when the curve has been made.

2. A machine for making pyjama frogs from tape having slideable edge cords comprising the combination of means for gripping the tape at one edge, means for pulling the cord in the other edge to form a loop in the tape, and means synchronized with the pulling means for changing the effective point at which the tape is gripped, thus determining the curvature of the loop.

3. A machine for making pyjama frogs from tape having slideable edge cords comprising the combination of means for gripping the tape at one edge, means for pulling

the cord in the other edge to form loops in the tape, and means synchronized with the pulling means for changing the effective point at which the tape is gripped, thus determining the curvature and position of the loops.

4. A machine for making pyjama frogs from tape having slidable edge cords comprising the combination of means for gripping the tape at one edge, means for pulling the cord in the other edge to form loops in the tape, and means synchronized with the pulling means for moving the gripping means forward in the direction of movement of the pulling means, thus advancing the effective point at which the tape is gripped and determining the curvature and position of the loops.

5. A machine for making pyjama frogs from tape having slidable edge cords comprising the combination of a carriage, means on the carriage for seizing one of the edge cords, means for moving the carriage across the machine to draw out a unit length of tape, means for gripping the tape at the other edge to prevent further bodily movement thereof and means synchronized with the carriage for changing the effective point at which the tape is gripped as further movement of the carriage pulls the seized cord, thus forming in the tape loops of predetermined curvature and position.

6. A machine for making pyjama frogs from tape having slidable edge cords comprising the combination of a longitudinal plate, a roller adjacent the plate, a carriage, means on the carriage for seizing one of the edge cords, means for moving the carriage across the machine to draw out a unit length of tape between the plate and the roller, means for causing the roller and plate to grip the other edge of the tape to prevent further bodily movement thereof and means synchronized with the carriage for advancing the roller along the plate as further movement of the carriage pulls the free cord, thus forming in the tape loops of predetermined curvature and position.

7. A machine for making pyjama frogs from tape having slidable edge cords comprising the combination of a movable carriage, means on the carriage for seizing one of the edge cords, means for moving the carriage across the machine to draw out a unit length of tape from a spool, means for gripping the tape at the other edge when the unit length has been drawn out, to prevent further bodily movement thereof, means for cutting the unit length from the spool, and means for changing the effective point at which the tape is gripped as further movement of the carriage pulls the seized cord, thus forming in the tape loops of predetermined curvature and position.

8. A machine for making pyjama frogs

from tape having slidable edge cords comprising the combination of a movable carriage, means on the carriage for seizing one of the edge cords, means for moving the carriage across the machine to draw out a unit length of tape from a spool, means for gripping the tape at the other edge when the unit length has been drawn out, to prevent further bodily movement thereof, means for cutting the unit length from the spool, means for changing the effective point at which the tape is gripped as further movement of the carriage pulls the seized cord, thus forming in the tape loops of predetermined curvature and position and means for returning the carriage to seize a new piece of tape.

9. A machine for automatically and continuously making pyjama frogs from tape having slidable edge cords comprising the combination of means for holding a spool of tape, a reciprocable carriage for seizing the tape by one of its edge cords, drawing it across the machine and continuing the pull to loop the tape, reciprocable means for gripping the unit length of tape unwound by the carriage at its other edge and intermediate its ends and advancing in timed relation with the carriage as the latter pulls the free cord to loop the tape, means for severing the unit length from the spool before the looping action begins and means for reciprocating the carriage and gripping means across the machine.

10. A machine for making pyjama frogs from tape having slidable edge cords comprising the combination of means for seizing one of the edge cords and drawing a unit length of tape across the machine, and means for gripping the other edge of the tape intermediate its ends to prevent further bodily movement thereof, whereby further movement of the moving means pulls the edge cord and curves the tape.

11. A machine for making pyjama frogs from tape having slidable edge cords comprising the combination of a plate against which the tape lies, a gripping roller for pressing one edge of the tape against the plate to hold the tape against bodily movement, means for pulling the cord in the other edge to form loops in the tape, and means for moving the roller forward in the direction of movement of the pulling means, thus determining the curvature and position of the loops.

12. A machine for making pyjama frogs from tape having slidable edge cords comprising the combination of a plate against which the tape lies, a gripping roller for pressing one edge of the tape against the plate to hold the tape against bodily movement, means for pulling the cord in the other edge to form loops in the tape, and means

- for moving the roller forward step-by-step in the direction of movement of the pulling means, thus determining the curvature and position of the loops. 100
- 5 13. A machine for making pyjama frogs from tape having slideable edge cords comprising the combination of a plate against which the tape lies, a gripping roller for pressing one edge of the tape against the plate to hold the tape against bodily movement, means for pulling the cord in the other edge to form loops in the tape, and means for moving the roller forward in the direction of movement of the pulling means, thus 10 determining the curvature and position of the loops, a fixed rack, and a pinion co-axial with the roller meshing with the rack for positively rotating the roller as it moves forward. 150
- 10 14. A machine for making pyjama frogs from tape having slideable edge cords comprising the combination of a transversely movable plate, a roller positioned adjacent the plate, a carriage, means on the carriage 20 for seizing the lower edge cords of the tape, means for moving the carriage to draw a unit length of tape between the plate and the roller, means for moving the plate transversely to grip the upper edge of the tape 25 between the plate and the roller and prevent further bodily movement thereof, and means for moving the roller along the plate to advance the effective point at which the tape is gripped as further movement of the carriage pulls the lower edge cord, thus forming in the tape loops of predetermined curvature and position. 30
- 15 15. A machine for making pyjama frogs from tape having slideable edge cords comprising the combination of means for holding a spool of tape, means for seizing one of the edge cords and drawing a unit length of tape across the machine, means for gripping the other edge of the tape after the unit length has been drawn out to prevent further bodily movement thereof, means for cutting the unit length from the spool, means for continuing the pull on the seized cord to form loops in the tape, means for advancing the effective point at which the tape is gripped as the pulling proceeds, thus determining the curvature and position of the loops, and means for cutting off the outer end of the pulled cord when the frog is 45 complete. 50
- 60 16. A machine for making pyjama frogs from tape having slideable edge cords comprising the combination of means for holding a spool of tape, a carriage for seizing one of the edge cords and drawing a unit length of tape across the machine, means for gripping the other edge of the tape after the unit length has been drawn out to hold it against further bodily movement, whereby further movement of the carriage will 65
- loop the tape, means for cutting the unit length from the spool, means for returning the carriage to seize a new piece of tape, and means for stripping one of the cords at the forward end of the new tape to enable the carriage to seize it. 70
- 75 17. In a machine for making pyjama frogs from tape having slideable edge cords by pulling one of the cords while gripping the tape at varying points along the other edge, the combination of means for holding a spool of tape, means for stripping the forward end of one of the edge cords, and means for seizing the stripped end and unwinding a unit length of tape from the 80 spool. 85
- 80 18. In a machine for making pyjama frogs from tape having slideable edge cords by pulling one of the cords while gripping the tape at varying points along the other edge, the combination of means for holding a spool of tape, a finger pivoted adjacent the forward end of the tape, means for swinging the finger against the end of the tape and between the two cords to push back the intermediate fabric and strip the ends of the cords, and means for seizing one of the stripped cords. 90
- 90 19. In a machine for making pyjama frogs from tape having slideable edge cords by pulling one of the cords while gripping the tape at varying points along the other edge, the combination of means for holding a spool of tape, means for unwinding a unit length of tape from the spool, means for cutting off the unit length, and means associated with the cutting means for stripping the forward ends of the cords. 95
- 100 20. A machine for making pyjama frogs from tape having slideable edge cords comprising the combination of means for holding a spool of tape, means for stripping the forward ends of the cords, means for seizing one of the stripped cords and unwinding a unit length of tape from the spool, means for cutting the unit length from the spool, means for gripping the unit length at the other edge and intermediate its ends to prevent further bodily movement whereby further pull exerted on the free cord will loop the tape and means for advancing the effective point at which the tape is gripped as the free cord is pulled thus determining the curvature and positions of the loops. 110
- 110 21. A machine for making pyjama frogs from tape having slideable edge cords comprising the combination of means for holding a spool of tape, means for stripping the forward ends of the cords, means for seizing one of the stripped cords and unwinding a unit length of tape from the spool, means for cutting the unit length from the spool, means for gripping the unit length at the other edge and intermediate its ends to prevent further bodily movement whereby fur- 120
- 125
- 130

ther pull exerted on the free cord will loop the tape, means for advancing the effective point at which the tape is gripped as the free cord is pulled thus determining the curvature and positions of the loops, and means for cutting off the extending cord from the completed frog.

22. A machine for making pyjama frogs from tape having slidable edge cords comprising the combination of means for holding a spool of tape, a finger pivoted adjacent the forward end of the tape, means for swinging the finger against the fabric of the tape intermediate the cords to strip the latter, a plate, a roller situated adjacent the plate, a carriage, means on the carriage for seizing one of the stripped cords, means for moving the carriage to draw a unit length

of tape from the spool between the roller and the plate, means for cutting the unit length of tape from the spool, means for moving the plate toward the roller to grip the other edge of the tape intermediate its ends and prevent further bodily movement thereof, whereby further pull exerted on the free cord will loop the tape, means synchronized with the carriage for moving the roller step by step along the plate to advance the effective point at which the tape is gripped, thus determining the curvature and position of the loops, and means for cutting off the extending cord from the completed frog.

In testimony whereof I affix my signature.

LOUIS H. MORIN.

CERTIFICATE OF CORRECTION.

Patent No. 1,639,098.

Granted August 16, 1927, to

LOUIS H. MORIN.

It is hereby certified that error appears in the above numbered patent requiring correction as follows: In the grant, heading to the drawings, and throughout the specification, for the word "pyjama" read "pajama"; and that the said Letters Patent should be read with this correction therein that the same may conform to the record of the case in the Patent Office.

Signed and sealed this 20th day of December, A. D. 1927.

Seal.

M. J. Moore,
Acting Commissioner of Patents.
